UNITED STATES PATENT OFFICE.

PAUL A. STOVER, OF RACINE, WISCONSIN, ASSIGNOR TO THE STOVER SIGNAL ENGINEERING CO., OF RACINE, WISCONSIN, A CORPORATION OF DELAWARE.

DESIGN FOR A VEHICLE SIGNAL-LIGHT CASING.

Application filed January 8, 1926. Serial No. 16,005. Term of patent 14 years.

To all whom it may concern:

Be it known that I, PAUL A. STOVER, a citizen of the United States, residing at Racine, in the county of Racine and State of Wisconsin, have invented a new, original, and ornamental Design for Vehicle Signal-Light Casing, of which the following is a specification, reference being made to the

drawing, forming a part thereof in which—

Fig. 1 is a front elevation of a vehicle signal light casing showing my new design.

Fig. 2 is a side elevation thereof.

I claim:

The ornamental design for a vehicle signal light casing substantially as shown.

PAUL A. STOVER.
